(57) **CLAIM**

The ornamental design for a light-emitting diode luminaire, as shown and described.

DESCRIPTION

FIG. 1 is a perspective view of the front and bottom of a light-emitting diode luminaire showing my new design;

FIG. 2 is a front view thereof;

FIG. 3 is a rear view thereof;

FIG. 4 is a top plan view, a bottom view being a mirror image thereof; and,

FIG. 5 is a right side view, a left side view being a mirror image thereof.

The portions shown in broken lines are for illustrative purposes only and form no part of the claimed design.
